UNITED STATES PATENT OFFICE

FLORENCE C. BIGGERT, JR., OF CRAFTON, AND JOHN A. SMITMANS, OF PITTSBURGH, PENNSYLVANIA, ASSIGNORS TO UNITED ENGINEERING & FOUNDRY COMPANY, OF PITTSBURGH, PENNSYLVANIA, A CORPORATION OF PENNSYLVANIA

CROP END DISCHARGING APPARATUS

Application filed June 16, 1930. Serial No. 461,327.

Our invention relates to apparatus for discharging, out of the path of the incoming strip, the waste ends, generally referred to as "crop" ends, which are produced by cutting off the rough ends of lengths of metal strip as they emerge from a rolling mill or the like.

The ends of metal strip, as originally produced in a rolling mill, are rough, and it is common practice to cut them off. In many instances this gives rise to a need for getting the cropped end out of the way of the oncoming strip. As one example,—where the strip comes from the rolling mill to a flying cutter, or like device, by which it is cut into lengths as it progresses forward, and is then passed on to a roller table or equivalent means for receiving it, the rough leading end is first cut off, and it is desirable to get this cropped end out of the way of the cut length which immediately follows it forward. It is the principal object of our invention to provide an apparatus by means of which this can be accomplished easily and quickly, and which will be simple of construction and convenient to use.

A discharging apparatus constructed in accordance with our invention is described, by way of example, in the following specification, and shown in the accompanying drawings, as associated with a flying cutter for cutting strip into lengths as it emerges from a rolling mill, though it will be understood that the invention has usefulness in connection with numerous other forms of installation in which it is desirable that material be discharged.

In the drawings:

Fig. 1 is a plan, with the blade of the flying cutter removed;

Fig. 2 is a side elevation; and

Fig. 3 is a section on the line III—III of Fig. 1, looking in the direction of the arrows.

Referring now to these drawings, 10 designates a framework carrying driven rolls 11 which continuously feed forward the metallic strip *a*, the latter being guided by adjustable side guides 12 and 13. The progressing strip *a* passes onto an anvil roll 14 with which cooperates the blade 15 of a flying cutter, the

latter being operated periodically so as to cut the strip into predetermined lengths. The flying cutter is shown in Fig. 1 as just having cut off the rough leading end of the strip, to produce the "crop" end designated *b*. 55

Adjustably mounted, to correspond with the adjustment of the side guides 12, upon the framework of the flying cutter 15, at the discharge side of the anvil roll 14, is a rail 16, disposed longitudinally in the direction 60 of travel of the strip. This rail supports, at one side, the issuing lengths of strip and, further, when a waste end (indicated at *b*) is cut off operates to support one side of such crop end as the latter issues under its 65 own momentum from the flying cutter, it being understood that the operation is rapid, a strip speed of 900 feet per minute being ordinary. The other side of the crop end is unsupported, and thus the leading end of 70 this side (the upper right-hand corner of the crop end, as seen in Fig. 1) drops downward.

Separated an appropriate distance from the discharge side of the flying cutter is a 75 roller table 17, or similar device for receiving the cut lengths of strip. Laterally adjustable upon the framework of this table is a relatively short receiving rail 18, which projects towards the flying cutter in the same general 80 line as the rail 16. Likewise projecting towards the flying cutter, and adapted to receive and support the sides of the cut lengths of strip opposite to those which are received and supported by the short rail 18, is an adjustable, relatively long receiving rail 19. The rails 18 and 19 are curved downward 85 at their ends, as shown in Fig. 2, so as to prevent any chance of the ends of the cut off lengths of strip drooping down and passing beneath instead of above the rails. The under 90 sides of the rails 18 and 19 are formed with inclined edges 18*a* and 19*a* respectively.

When the rough leading end of the strip is cut off, the upper right-hand corner (as 95 seen in Fig. 1) of the crop end *b* drops downward, as referred to above, and passes beneath the rail 19 as the crop end emerges, under its momentum, from the flying cutter. Since the ends of the rails 16 and 18 are relatively 100

widely separated, by the time the leading edge of the cropped end reaches the short rail 18, this edge will also be unsupported and will have dropped downward, and will also have been urged downward because of the engagement of the opposite side of the leading edge with the incline 19a of the receiving rail 19, so as to pass beneath the rail 18. The crop end is thus directed downward, out of the path of movement of the cut lengths of strip, and falls into an inclined chute 20 whence it slides to any desired point, such as into a receptacle 21 where the ends can accumulate conveniently for removal. To direct the trailing corner of the crop end as it falls onto the chute 20, an inclined plate 22 is secured to the framework of the flying cutter, beside the rail 16. This plate 22 is conveniently made removable so that, if desired, different sizes of plate can be used according to different adjustments of the rail 16.

The ordinary cut pieces of strip, being in lengths greater than that of the crop ends, are supported, at the side opposite to the rail 16, by reason of their connection with the main body of the strip until their leading edges reach, or nearly reach, the receiving rails 18 and 19, the downwardly curved ends of these rails looking after any such slight drooping as may occur. Thus these pieces pass over the rails 18 and 19 and into the receiving roller table 17.

Our invention, therefore, by an apparatus of exceptionally simple construction and great ease of adjustment, enables the crop ends to be deflected out of the path of the issuing strip and to be discharged and collected in a manner convenient for subsequent removal.

40 We claim:

1. The combination with a device for cutting strip material in motion, of a member for receiving and supporting one edge portion of the advancing end of the material, said member being spaced from said device, and means associated with said device for supporting the opposite edge portion only of said material as it issues from said device, whereby relatively long pieces of material will pass onto said receiving member but relatively short pieces will drop down at one edge portion so as to pass beneath the same.

2. The combination with a device for cutting strip material in motion, of a member for receiving and supporting one edge portion of the advancing end of the material, said member being spaced from said device, a second member for receiving and supporting the opposite edge portion of the advancing end of the material, said second-named member being spaced from said device by a greater distance than said first-named member, and means disposed substantially opposite said second-named member for supporting said material as it issues from said device,

whereby relatively long pieces of material will pass onto said receiving members but relatively short pieces will pass beneath the same.

3. The combination with a device for cutting strip material in motion, of a member for receiving and supporting one edge portion of the advancing end of the material, said member being spaced from said device, a laterally inclined chute disposed beneath the space between said member and said device, and means associated with said device for supporting the opposite edge portion of said material as it issues from said device, whereby relatively long pieces of material will pass onto said receiving member but relatively short pieces will drop down at one edge portion so as to pass beneath the same and fall into said chute.

4. The combination with a device for cutting strip material in motion, of a member for receiving and supporting one edge portion of the advancing end of the material, said member being spaced from said device and having an inclined portion beneath the same, a second member for receiving and supporting the opposite edge portion of the advancing end of the material, said second-named member being spaced from said device by a greater distance than said first-named member, and means disposed substantially opposite said second-named member for supporting said material as it issues from said device, whereby relatively long pieces of material will pass onto said receiving members but the corners of relatively short pieces will pass beneath said first-named member and be deflected downward by the inclined portion thereof so as to cause the opposite corners to pass beneath said second-named member.

In testimony whereof, we hereunto sign our names.

FLORENCE C. BIGGERT, JR.
JOHN A. SMITMANS.
